TIME AND REMOTE CONTROL SYSTEM

Clarence W. Nessell, Forest Park, Ill., assignor to
 Minneapolis-Honeywell Regulator Company,
 Minneapolis, Minn., a corporation of Delaware

Application August 24, 1935, Serial No. 37,777

3 Claims. (Cl. 250—20)

This invention relates to combined time control and remote control systems and has particular utility in controlling radio sets.

It is an object of this invention to provide a control system whereby a mechanism may be remotely positioned, or may be moved to predetermined positions at predetermined intervals.

More specifically, it is an object of this invention to provide a control system for a radio set whereby the condenser shaft thereof may be remotely operated, and whereby the shaft may be placed in predetermined positions at predetermined times.

Other objects and advantages will become apparent to those skilled in the art upon reference to the accompanying specification, claims and drawing, in which drawing is diagrammatically illustrated the control system of this invention.

Although this invention is of general utility it is shown as applied to a condenser shaft 10 of a radio set. The condenser shaft 10 is positioned by a gear 11 secured to the condenser shaft and 25 in engagement with a gear 12 mounted on a shaft 13, so that upon rotation of the shaft 13 the condenser shaft 10 is also rotated. Also secured to the shaft 13 is a gear 14 which is driven through a reduction gear train 15 by motor 30 rotors 16 and 17. The motor rotors 16 and 17 are operated by field windings 18 and 19, respectively, the arrangement being such that upon energization of the field winding 18 shaft 13 is moved in one direction, and upon energization 35 of the field winding 19 the shaft 13 is moved in the opposite direction.

Also located on the shaft 13 is a bevelled gear 20 engaging a bevelled gear 21 carrying an abutment member 22. The abutment member 22 is 40 made of insulated material and carries a slider 23 adapted to slide across a balancing potentiometer coil 24. Upon rotation of the shaft 13 the slider 23 is moved across the coil 24 in a direction depending upon the direction of rotation of the shaft 13. The abutment member 22 is likewise provided with fingers 25 and 26. Upon 45 movement of the abutment member 22 to an extreme counterclockwise position the finger 25 is adapted to engage a contact 27 to break contact between this contact 27 and a stationary contact 28. Likewise, upon movement of the abutment 50 22 to an extreme clockwise position, the finger 26 is adapted to engage a contact 29 to move the contact 29 out of engagement with a

stationary contact 30. In this manner the contacts 27, 28, 29 and 30 form limit switches.

This invention contemplates the use of a time switch and any time switch known in the art may be utilized therein. However, for purposes of 5 illustration, I have shown this time switch to comprise a rotor 31 operated by a field winding 32 to rotate a shaft 34 at a constant speed through a reduction gear train 33. Adjustably mounted on the shaft 34 are cams 35, 36, 37, 38 10 and 39, which are moved in a clockwise direction by the shaft 34. These cams contain equally spaced high dwells which are adapted to sequentially engage contact arms 40, 41, 42, 43 and 44, respectively. The contact arms 40, 41, 42, 43 15 and 44 are adapted to sequentially engage contacts 45, 46, 47, 48 and 49, the time of engagement of the contacts by the contact arms being dependent upon the length of the dwells on the cams, and upon the speed of rotation of the 20 shaft. For purposes of illustration, the high dwells are designed to maintain their respective contact arms in engagement with the associated contacts for a period of one hour, and since five cams are used in this exemplification 25 it takes five hours for the shaft 34 to complete one revolution. The number of cams, the length of the cam dwells and the speed of the shaft 34 may be varied to suit the particular installation. The contacts 45, 46, 47, 48 and 49 are connected 30 by means of wires 50, 51, 52, 53 and 54, respectively, to sliders 55, 56, 57, 58 and 59, respectively. The sliders 55, 56, 57, 58 and 59 are adapted to be manually positioned along potentiometer coils 61, 62, 63 and 64, respectively, in any suitable 35 manner.

This invention also contemplates the use of a remotely located potentiometer which may take the form of a resistance coil 66, slidably engaged by a manually operated slider 65. A single pole 40 double throw switch is also utilized in this invention and may take any form, but for purposes of illustration in this application it is shown to comprise a switch arm 67 alternately engageable with spaced contacts 68 and 69. 45

Leading from some source of power, not shown, are line wires 70 and 71. Connected across these line wires is a primary 72 of a step-down transformer 73, having a secondary 74. One end of the secondary 74 is connected by a 50 wire 75 to one end of the field winding 32, and the other end of the secondary 74 is connected by a wire 76 to the other end of the field winding 32 to energize the field winding 32 to cause continuous operation of the time switch. 55

Also connected across the line wires 70 and 71 is a primary 71 of a step-down transformer 78, having a secondary 79. One end of the secondary 79 is connected by wires 80 and 81 and a protective resistance 82 to one end of a coil 83. In a like manner the other end of the secondary 79 is connected by a wire 84 and a protective resistance 85 to one end of a coil 86. The coils 83 and 86 are connected together at their inner ends. The junction of wire 81 and the protective resistance 82 is connected by wires 87 and 88 to one end of the resistance coil 66 of the remotely located potentiometer. In a like manner the junction of the wire 84 and protective resistance 85 is connected by wires 89 and 90 to the other end of the resistance coil 66 of the remotely located potentiometer. The junction of the wires 80 and 81 is connected by a wire 91 to one end of the balancing potentiometer coil 24 and the other end of the balancing potentiometer coil 24 is connected by wires 93 and 92 to the junction of the wires 89 and 90. The potentiometer coils 60, 61, 62, 63 and 64 are connected across the wires 88 and 90 leading to the remotely located potentiometer by wires 94 and 95. Therefore, the potentiometer coils 60, 61, 62, 63, 64 and 66 are located in parallel. The junction of the coils 83 and 86 is connected by wires 96 and 97 to the switch arm 67 and by wires 96 and 98 to the slider 23 associated with the balancing potentiometer coil 24. The contact arms 40, 41, 42, 43 and 44 of the time switch are connected by wires 99 and 100 to the contact 68 associated with the switch arm 67. The contact 69 is connected to the slider 65 of the remotely located potentiometer by the wire 101. The junction of the wires 92 and 93 is connected by a wire 102 to a pivoted switch arm 103. Cooperating with this pivoted switch arm 103 are spaced contacts 104 and 105, the contact 104 being connected to the contact 29 of the limit switch by the wire 106, and the contact 105 being connected to contact 28 of the limit switch by a wire 107. Contact 30 is connected by a wire 108 to one end of the field winding 19, and the contact 27 is connected by a wire 109 to one end of the field winding 18. The other ends of the field windings 18 and 19 are connected together and by a wire 110 to the junction of wires 87 and 88. The switch arm 103 is operated by an armature 111 through a spring 112 so that when the coil 83 is energized more than the coil 86 the switch arm 103 is moved into engagement with contact 104, and when the coil 86 is energized more than the coil 83 the switch arm 103 is moved into engagement with the contact 105.

From the above wiring connections it is seen that the left hand ends of the secondary 79, the coil 83 and the potentiometer coils 60, 61, 62, 63 and 64, the upper end of the potentiometer coil 66 and the right hand end of the balancing potentiometer 24 are connected together. Likewise, the right hand ends of the secondary 79, the coil 86, the potentiometer coils 60, 61, 62, 63 and 64, the lower end of the potentiometer coil 66, and the left hand end of the balancing potentiometer coil 24 are connected together. Also, it is seen that the junction of the coils 83 and 86, and the sliders 23 and 65 are connected together when the switch arm is in engagement with the contact 69. Likewise, it is seen that when the switch arm 67 is in engagement with the contact 68, one or the other of the sliders 55, 56, 57, 58 and 59 are connected to the slider 23 and the junction of the coils 83 and 86.

Therefore, the coils 83 and 86, secondary 79, the balancing potentiometer 24 and the control potentiometers 60, 61, 62, 63, 64 and 66 are connected in parallel.

Assume the parts in the position shown in the drawing with the switch arm 67 in engagement with the contact 68, whereby the slider 65 of the remotely located potentiometer is electrically connected to the coils 83 and 86. The slider 65 and the slider 23 are located in a mid position, consequently, the coils 83 and 86 are equally energized to maintain the switch arm 103 in its mid position to maintain the condenser shaft 10 also in its mid position. Movement of the slider 65 upwardly with respect to the coil 66 causes shunting or short-circuiting of the coil 83 to decrease the energization thereof and increase the energization of the coil 86. Due to this unbalanced relationship of the coils 83 and 86, the switch arm 103 is moved into engagement with the contact 105 to complete a circuit from the secondary 79 through wires 84, 89, 92 and 102, switch arm 103, contact 105, wire 107, contacts 28 and 27, wire 109, field winding 18 and wires 110, 87, 81 and 80, back to the secondary 79. This causes energization of the field winding 18 to rotate the shaft 13 in a direction to move the slider 23 to the left with respect to its resistance coil 24. Movement of the shaft 13 also causes movement of the condenser shaft 10 of the radio set. Movement of the slider 23 towards the left causes short-circuiting or shunting of the coil 86 to decrease the energization thereof and to increase the energization of the coil 83, it being remembered that the energization of the coil 83 was increased and the energization of the coil 83 was decreased by the upward movement of the slider 65 of the remotely located potentiometer. When the slider 23 has moved sufficiently far to the left to re-balance the energization of the coils 83 and 86 the switch arm 103 is moved out of engagement with the contact 105 to the mid position shown in the drawing to break the circuit through the field winding 18 to stop rotation of the shaft 13.

Movement of the slider 65 downwardly causes short-circuiting or shunting of the coil 86 to decrease the energization thereof and increase the energization of the coil 83. This causes movement of the switch arm 103 into engagement with the contact 104 to complete a circuit from the secondary 79 through wires 84, 89, 92 and 102, switch arm 103, contact 104, wire 106, contacts 29 and 30, wire 108, field winding 19 and wires 110, 87, 81 and 80, back to the secondary 79. Completion of this circuit causes energization of the field winding 19 to rotate the shaft 13 and, consequently, the condenser shaft 10 in the opposite direction and to move the slider 23 to the right with respect to its resistance coil 24. Movement of the slider 23 towards the right causes shunting or short-circuiting of the coil 83 to decrease the energization thereof and increase the energization of the coil 86, it being remembered that the coil 83 was energized more than the coil 86 by the downward movement of the slider 65 of the remotely located potentiometer. When the slider 23 has moved sufficiently far to the right the coils 83 and 86 are rebalanced to move the switch arm 103 out of engagement with the contact 104 to the mid position shown in the drawing. This causes deenergization of the field winding 19 to stop further rotation of the shaft 13 and, consequently, the condenser shaft 10.

Over-travel of the condenser shaft 10 beyond its extreme positions is prevented by the limit switches comprising the contacts 21, 28, 29 and 30 which break the circuit to the field windings 5 18 or 19 when the condenser shaft 10 has been moved to either extreme position. The protective resistances 82 and 85 are provided in the control circuit to prevent burning out of the coils 83 and 86 when the slider 65 is moved to either 10 extreme position.

From the above it is seen that I have provided a remote control system for positioning a condenser shaft of a radio set or for positioning any other mechanism whereby the condenser shaft 15 or other mechanism is made to assume a position corresponding to the position of a slider of a remotely located potentiometer. By reason of this construction, the stations, the reception of which is desired, may be selected from some 20 remote point.

This invention also contemplates a system of control where a plurality of stations may be selected in advance, and wherein these stations may be tuned in at predetermined times. In 25 order to obtain this time control of the radio set the switch arm 61 is moved into engagement with the contact 68 and by reason of this movement one of the sliders 55, 56, 57, 58 or 59 is electrically connected to the junction of the coils 30 83 and 86. The time switch determines the slider which shall be so connected. The slider 55 may be adjusted for one station, slider 56 may be adjusted for another, and likewise the sliders 57, 58 and 59 may be adjusted for other stations, 35 suitable dial mechanism, not shown, being provided to facilitate the proper movement of the sliders. With the parts in the position shown in the drawing, and with the switch arm 61 in engagement with the contact 68, the slider 57 associated with the resistance coil 62 is in control 40 of the condenser shaft 10. Since the slider 57 is in a mid position the condenser shaft 10 is likewise in a mid position. The station obtained by this time setting will be received until the 45 contact arm 42 is moved out of engagement with the contact 41. Movement of the contact arm 43 into engagement with the contact 48 places the slider 58 in command and the condenser shaft 10 is moved to a new position as determined 50 by the position of the slider 58 in the manner pointed out above with respect to movement of the slider 65. Like operation is obtained when the contact arm 44 is moved into engagement with the contact 49, or when the contact arms 40 and 41 are moved into engagement 55 with the contacts 45 and 46. In this manner any station may be received and the time at which this station shall be received may be definitely ascertained.

From the above it is seen that I have not only provided a remote control system for a radio set or other mechanism, but I have provided a time control system wherein any number of predetermined positions of the condenser shaft or other mechanism may be selected in advance, 60 and wherein the condenser shaft or other mecha-

nism may be moved to these positions at predetermined times.

Although I have disclosed one form of my invention, it is apparent that other forms thereof 5 may become apparent to those skilled in the art and, consequently, this invention is to be limited only by the scope of the appended claims and the prior art.

I claim as my invention:

1. In a system of the class described, the combination of a condenser shaft for a radio set, motor means for positioning said condenser shaft, and a remotely located variable resistance type controller for controlling said motor means, means for causing the motor means to position 10 the condenser shaft in proportional correspondence to the adjustments of said controller, a plurality of other variable resistance type controllers for controlling also said motor means, each of said plurality of other controllers being 15 adjustable, means for causing the motor means to move said condenser shaft to predetermined positions as determined by the adjustment of said other controllers, time controlled means for placing the control of said motor means under 20 the control of any of said plurality of other controllers, and means for selectively placing the motor means under the control of the remotely located controller or the plurality of other controllers whereby the radio set may be remotely 25 controlled or tuned into various stations at predetermined times.

2. In a system of the class described, the combination of a mechanism to be controlled, motor means for positioning said mechanism, a plurality of separate, remotely located resistances for controlling said motor, each resistance having 30 a contact arm manually adjustable to any point thereon, means for causing the motor to adjust 35 said mechanism to assume a position determined 40 by the position of the contact arm, and time actuated means for selectively placing said motor under the control of any one of said resistances.

3. In a system of the class described, the combination of a condenser shaft for a radio set, 45 motor means for positioning said condenser shaft, a first controller for said motor comprising a resistance element and a contact arm capable of being positioned at any point on said resistance element, control means for causing the motor to adjust the condenser shaft to assume a 50 position which is determined by the position assumed by said contact arm, a second controller comprising a plurality of separate resistance elements, each having a contact arm capable of being 55 positioned at any point on its resistance element, said control means causing the motor to adjust the condenser shaft to assume a position which is determined by the position assumed by any one of said contact arms, selecting means for 60 determining which of the controllers shall be in control of said motor, and time actuated means for placing the motor under control of any one of said resistance elements of the second controller.

CLARENCE W. NESELL.
